Primary Examiner — Lauren R Calve(74) *Attorney, Agent, or Firm* — Dickinson Wright PLLC; Mark E. Scott**CLAIM**

The ornamental design for a stackable pant hanger, as shown and described.

DESCRIPTION

FIG. 1 is a perspective view of the front of a stackable pant hanger;

FIG. 2 is a perspective view of the rear of the stackable pant hanger;

FIG. 3 is a front view of the stackable pant hanger;

FIG. 4 is a rear view of the stackable pant hanger;

FIG. 5 is a top view of the stackable pant hanger;

FIG. 6 is a bottom view of the stackable pant hanger;

FIG. 7 is a view of one end of the stackable pant hanger; and,

FIG. 8 is a view of the other end of the stackable pant hanger.
